Peter Nielsen, Omaha, Nebr., assignor to Jubilee
Manufacturing Company, Omaha, Nebr., a cor-
poration of Nebraska

Application February 19, 1941, Serial No. 99,119

Term of patent 7 years

To all whom it may concern:

Be it known that I, Peter Nielsen, a citizen of the United States, residing at Omaha, in the county of Douglas and State of Nebraska, have invented a new, original, and ornamental Design for an Automobile Horn Keyboard Switch, or the Like, of which the following is a specification, reference being had to the accompanying drawing, forming part thereof.

Figure 1 is a side elevational view of an automobile horn keyboard switch showing my new design.

Figure 2 is a top plan view thereof.
Figure 3 is an end elevational view thereof.
The dominant feature of my design resides in the portions shown in full lines.

I claim:

The ornamental design for an automobile horn keyboard switch or the like, as shown and described.

PETER NIELSEN.
